UNITED STATES PATENT OFFICE.

LOUIS JABNER, OF JERSEY CITY, NEW JERSEY.

CLASP.

Application filed March 2, 1922. Serial No. 540,503.

To all whom it may concern:

Be it known that I, LOUIS JABNER, a citizen of the United States, and a resident of Jersey City, in the county of Hudson and State of New Jersey, have invented a new and Improved Clasp, of which the following is a full, clear, and exact description.

This invention has relation to separable fasteners and refers more particularly to an improvement in clasps for detachably coupling the ends of necklaces, bracelets or other similar articles of jewelry.

As one of its principal objects the invention aims to provide a clasp which insures a positive locking of the interengageable elements thereof to reduce to a minimum disengagement of the same and loss of the article with which it is associated.

As a further object the invention aims to provide a simple and inexpensive clasp including interengageable elements which are provided with means to facilitate ready engagement or disengagement of the same.

The invention further aims to provide a clasp which may be constructed to provide an extremely minute device of this character without detracting from its strength or holding qualities.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

40 In the drawing—

Figure 1 is a plan view of a clasp constructed in accordance with the invention with the cover plate removed.

Fig. 2 is a sectional plan view thereof.

45 Fig. 3 is a side elevation of the same.

Referring to the drawings by characters of reference, the clasp comprises interengageable male and female members 10 and 11, the former comprising a pin or shank 12 provided with an eye 13 at one extremity for associating the same with the links or string of a necklace. The latter or female member 11 embodies an outer shell or casing 14 of any suitable exterior configuration and provided with an open side which is closed by

a cover plate 15 adapted to be burnished, soldered, or otherwise secured thereto in any suitable manner. Within the casing 14 a yoke or frame 16 is arranged, the side arms 17 of which converge toward each other at 60 one end of the frame to provide therebetween a space of gradually decreasing widths. The end member 18 of the frame and the end wall 19 of the casing or shell 14 are respectively provided with aligned 65 central apertures 20 and 21 which receive a tubular sleeve 22 extending therethrough and provided with laterally projecting ears 23. The inner end of the sleeve 22 is provided with an enlarged boss 24 from the 70 inner end of which a sleeve section 25 projects in axial alignment to the sleeve 22. The boss 24 is provided with a transverse opening 26 in which a pair of spherical members or balls 27 are arranged. A coiled 75 contractile spring 28 surrounds the sleeve section 25 and bears at its opposite extremities respectively against the boss 24 and the remaining end member 29 of the frame or yoke member 16. The casing 14 of the 80 female clasp member is provided at the remaining end wall 30 with an eye 31 for attaching said member to the opposite end link of the chain or string of the necklace or bracelet with which the clasp is associated. 85

In use and operation of the clasp, the shank or pin 12 of the male member 10 is inserted within the sleeve 22 and sleeve section 25 to separate the balls 27, the sleeve, the sleeve member, boss and balls being 90 moved axially against the action of the spring 28 to dispose the peripheral surface of the balls toward the center or wider portion of the space defined by the side arms 17. Upon completion of the inserting action, the 95 spring 28 will react and force the sleeve, the sleeve member, boss and balls in the opposite direction to impinge the periphery of the balls at diametrically opposite points against the inner surface of the side legs 100 of the yoke or frame and against the pin or shank 12 at diametrically opposite points of its periphery. This serves as a positive lock against the withdrawal or removal of the pin or shank 12 from the sleeve and sleeve member. To effect the release of the pin or shank 12, the user or operator presses upon the ears 23 to shift the sleeve and sleeve member axially against the action of the spring whereby the impingement of the balls 110

against the sides of the shank or pin and the inner surfaces of the side arms 17 is discontinued, leaving the pin or shank free for retraction. To prevent spreading of the converging extremities of the side arms 17, any space between the outer surface of said extremities is preferably filled by backing wedges 32.

I claim:

10. 1. A clasp including a male member comprising a shank and a female member comprising a shell having an opening through one end thereof, a yoke or frame arranged within said shell having an opening in the corresponding end registering with the shell opening, the yoke having side arms diverging toward said end, a sleeve extending through said opening and into the yoke, a medial boss on said sleeve having a transverse opening intersecting the bore of the sleeve, a pair of balls arranged in said opening and a spring surrounding the inner end of the sleeve and interposed respectively between the boss and the remaining end of the yoke for normally exerting a force to shift the sleeve toward the open end of the shell and force the balls toward each other for

gripping the shank of the male member when inserted within the sleeve.

2. A clasp including a male member comprising a shank and a female member comprising a shell having an opening through one end thereof, a yoke or frame arranged within said shell having an opening in the corresponding end registering with the shell opening, the yoke having side arms diverging toward said end, a sleeve extending through said opening and into the yoke, a medial boss on said sleeve having a transverse opening intersecting the bore of the sleeve, a pair of balls arranged in said opening and a spring surrounding the inner end of the sleeve and interposed respectively between the boss and the remaining end of the yoke for normally exerting a force to shift the sleeve toward the open end of the shell and force the balls toward each other for gripping the shank of the male member when inserted within the sleeve, and manipulating ears carried by the outer end of the sleeve for axially shifting the same to compress the spring for releasing the shank of the male member.

LOUIS JABNER.
